J. Hulcey, Atty.

UNITED STATES PATENT OFFICE

VERNON ANTHONY TRIER, OF LONDON, ENGLAND

VENTILATOR

Application filed August 8, 1928, Serial No. 298,388, and in Great Britain December 1, 1927.

This invention relates to ventilators for use with windows of the sliding sash type and has for its object to provide an improved form of the known louver or similar ventilator which is particularly, though not exclusively, applicable to vehicle windows.

According to this invention a louvered or like ported member is provided adapted to be secured as a separate fitting or unit in a detachable manner to the window or window frame so as to occupy part of the opening normally closed by the sliding window, thus providing for ventilation independently of the main window opening.

15 In a simple form the ventilator comprises a ported frame adapted to be secured to the upper edge of the window or sash so as to partake in its sliding movement, the ported frame occupying a space between the upper 20 edge of the window and the upper rail of the frame. The frame is provided with a sliding plate or the like to control the air admitted through the openings therein without altering the structure of the window frame 25 or of the sash.

A construction of ventilating device in accordance with this invention are illustrated by way of example in the accompanying drawings, in which

30 Figure 1 shows one construction in elevation,

Figure 2 is a cross-section on the line 2—2 of Figure 1 also showing the upper part of the sliding window,

35 Figure 3 is an end elevation of Figure 1,

Figure 4 shows the ventilator illustrated in Figure 1 placed in position.

In the construction shown in Figures 1—4, the ventilator comprises a rectangular metal 40 frame A in the form of an inverted U the parallel sides of which have ports A² provided with vertical louvers A¹ on the outer side. A shutter B furnished with an operating knob C is mounted to slide between

45 the two parallel sides of the frame A to control the ports A². The lower edges of the frame A form a channel D adapted to receive the upper edge of the sliding sash E to which the frame can be clamped. For this 50 purpose clamping screws F are provided,

furnished with distance pieces F¹ which limit the extent to which the sides can be drawn together and thus prevent damage to the glass. When the frame A is so attached, it slides with the sash E in the window guides 55 G so that if the sash is fully raised (as shown by dotted lines in Figure 4) the upper edge of the frame A engages in the groove G¹ in the upper rail of the window frame H. Air can therefore be admitted through the ports 60 A² without letting down the sash.

The frame A is preferably adjustable in length to suit the width of the window opening and therefore is provided at one or both ends with an extension piece J adapted to 65 slide within or upon the frame and furnished with a locking device such as a screw J¹ and also with a window-clamping screw F².

It will be understood that the particular form of louver or like hood to protect the 70 ports from the admission of rain or moisture may vary and that any known device to prevent draught or rattle may be employed without departing from this invention.

What I claim as my invention and desire 75 to secure by Letters Patent is:—

For use with windows of the kind comprising a frame and a sash adapted to slide therein, a ventilating device comprising a U-shaped frame having similar openings 80 formed in its parallel walls, means for detachably connecting the edges of the frame to the upper edge of the sliding sash so that the frame and sash can move as a unit within the window frame, a plate mounted to slide 85 between the parallel sides of the frame to control the ports therein, and a member adjustably connected to each end of the frame whereby the effective length of the frame can be varied to suit the width of the sliding sash 90 and window frame with which it cooperates.

In testimony whereof I have signed my name to this specification.

VERNON ANTHONY TRIER.
